UNITED STATES PATENT OFFICE.

HENRY H. SANFORD, OF MANSFIELD, OHIO, ASSIGNOR TO THE NEW METHOD STOVE COMPANY, OF MANSFIELD, OHIO, A CORPORATION OF OHIO.

DESIGN FOR A GAS HEATER OR SIMILAR ARTICLE.

Application filed August 3, 1925. Serial No. 14,300. Term of patent 3½ years.

To all whom it may concern:

Be it known that I, HENRY H. SANFORD, a citizen of the United States, residing at Mansfield, in the county of Richland and State of Ohio, have invented a new, original, and ornamental Design for a Gas Heater or Similar Article, of which the following is a specification, reference being had to the

accompanying drawing, which shows a perspective view of a gas heater showing my new design.

I claim:

The ornamental design for a gas heater or similar article, as shown.

HENRY H. SANFORD.
